UNITED STATES PATENT OFFICE.

JOHN C. DE PENNING, OF PORTLAND, OREGON, ASSIGNOR TO CENTRAL DOOR AND LUMBER COMPANY, OF PORTLAND, OREGON, A CORPORATION.

METHOD OF PATCHING.

Application filed July 19, 1926. Serial No. 123,572.

My invention relates to the art of wood-working, and has for its particular object the provision of a simple and efficient method of patching boards having surface imperfections such as pitch pockets. My invention has particularly to do with the sash and door industry, because in the latter industry the finished product is sold according to grade and the grade is established 10 by the number of surface imperfections present.

Much attention has been given to methods and devices for eliminating said imperfections and patching, but all patches as made 15 at present, either increase the cost of the products produced to such a degree that any saving in grade is nullified by the increased cost of production, or else the patching is done in such a manner that the patch is very 20 apparent so that the product frequently has to retain the lower grade.

The most common method of patching is shown and described in the United States Patent, No. 1,005,546 granted to William C. Hobart. By this method the pitch pocket or other imperfection is cut away by an elongated incision having relatively straight walls and square ends. The incision is formed by the kerf of a rotatable saw, and 30 a one-piece plug corresponding in shape to the incision thus made is glued and driven into the latter.

This method is deficient in the following particulars:

35 1. The square ended patches are very noticeable, especially in vertical grain lumber, because it is impracticable to select a strip of patching material which corresponds so closely in grain spacing and in width that 40 the grain of the wood can be matched exactly and thus the inserted patch is defined by the broken grain structure at each end.

45 2. It is necessary to give the plug inserted a slight amount of "draft" or taper so as to permit it to enter the vertical sided incision and thus the plug used does not correspond exactly in cross-section to the incision. The only portion of the side walls in contact with the plug is the surface edge 50 with which the tapered plug engages and is secured thereto by glue.

It is customary to sandpaper or otherwise dress off the patched surface after the plug is secured in place and such surface edge 55 thus glued is frequently so shallow that the

surface dressing removes the glued portion and permits the plug to drop out, and thus the trade has not taken kindly to a patched product, although it is equally as strong as a clear grade product.

I have discovered that the advantages in speed and inexpensiveness of the Hobart method can be retained and the disadvantages heretofore noted eliminated by forming the incision substantially wedge-shaped 60 in cross-section and cigar-shaped in plan and forming the plug to be inserted therein, of a plurality of sections corresponding in cross section to said incision. That is, plugs are used which are made up of a plurality 65 of pieces also wedge-shaped in section and said pieces are driven endwise and downwardly into the incision so that they are secured tightly in place along their entire widths and thus dressing the surface can 70 not remove the securing means for the patch to permit the latter to drop out. Making the patch cigar-shaped in section, that is, having pointed ends, tends to eliminate any 75 sharp break in grain structure for the reason that the break is distributed over a substantially larger area and the severing of the separate grains or annular rings is not in a transverse line.

I show in a co-pending application for 80 patent entitled, Patching Saw, filed July 19th, 1926, Serial No. 123,571, a rotatable tool for forming said incision such saw being provided with teeth formed about its periphery such teeth forming a knife-edged cutting 85 means in that the teeth diverge angularly at each side of the saw.

A further object of my invention is to provide a method of this character by which a minimum amount of material may be removed in forming an incision so that a 90 smaller patch may be inserted.

Pitch pockets, especially, are elongated and extend lengthwise of the grain and terminate in pointed ends and thus the saw 95 thus described may form an incision exceeding the surface defect only slightly, and because of the angular divergence of the cutting teeth of the patching saw the incision may be formed of a depth also exceeding that 100 of the defect only slightly. By making the plug wedge-shaped in section and sectional 105 I am able to use strips of patching material of uniform cross-section which will fill the incision exactly, independent of the depth 110

of the latter, and the patch will vary only in the excess amount of material to be dressed off.

Further details of my improved patching method, are hereinafter set out with reference to the accompanying drawings, in which:

Fig. 1 is a side elevation of a board in which an incision is made, by my improved saw, to remove a surface defect;

Fig. 2 is a transverse sectional view thru such saw and board;

Fig. 3 is a perspective view of said board with the incision thus made and with a sectional patch super-imposed above the incision;

Fig. 4 is a view similar to Fig. 1 with a three-piece sectional patch secured in place;

Fig. 5 is a fragmentary view of a board showing a pitch pocket.

Fig. 6 is a progressive perspective view of the above showing an incision formed by my method to remove such pitch pocket;

Fig. 7 is a similar progressive fragmentary perspective view showing one-half of a sectional plug set loosely in place;

Fig. 8 is a similar progressive perspective view showing said sectional plug secured in place and with one-half thereof dressed off.

Fig. 9 is a similar progressive fragmentary perspective view showing the finished patch; and

Fig. 10 is a sectional view taken on the line 10—10 in Fig. 7 transversely through the incision and thru the patch seated therein.

In Fig. 5, I show a pitch pocket a' , which is the usual surface imperfection to be eliminated. The grain structure or annular rings b tend to diverge about said pitch pocket to produce a wave or irregularity in the grain. That is, the pitch pocket a' tends to space the grain structure or rings b wider than normal and thus even if a patch made from the same board is inserted, the grain structure will differ and the patch will be very noticeable. By my method a pitch pocket or other imperfection a' is cut away by a cigar-shaped incision c or c' which is only slightly greater than the defect so as to cut away a minimum amount of material. Such incision is wedge-shaped in cross-section, as shown in Figs. 2 and 10, and preferably is formed by a rotatable saw d having divergent teeth d' formed about its periphery. Such teeth are beveled or diverge angularly along both sides of the saw blade as shown in Fig. 1, and thus cut away a wedge-shaped incision, and extend a substantial distance up both sides to permit an incision of considerable depth to be formed in the board.

As is evident, the further the saw is forced into the board the wider an incision will be formed, the walls of such incision, however,

diverging at a constant angle. To permit such saw to be movable to vary the depth of the cut, it is mounted upon a vertically adjustable shaft e and the board a to be acted upon is carried by a table f . Said table f may be moved and the saw fixed or be stationary and the saw movable longitudinally thereover, as well as vertically thereto.

In practice the teeth extend up the side of the saw about one inch and the saw is approximately five and one-half inches in diameter. Thus, pitch pockets up to about three inches in length can be cut away without moving the saw longitudinally relatively to the table but may be cut away merely by moving the saw vertically thereto. With short pitch pockets a two-piece plug g can be used to fill the incision as is shown in Figs. 6 to 10, inclusive. To eliminate a pitch pocket of greater length, however, it is necessary to move the saw relatively longitudinally of the table to produce an incision c' and to fill such an incision with a three-piece plug g' .

That is, short pitch pockets can be eliminated merely by depressing the saw thus forming an incision c having a base portion which is angularly disposed towards the surface in two directions and making equally divergent angles to the surface in opposite directions. In the incision c' , however, said angular base portions c'' are connected by a base portion c' which extends substantially parallel to the surface acted upon, and to patch an incision c' it is necessary to use three pieces, one piece substantially the length of the base portion c' and two other pieces substantially the length of each of the angular base portions c'' , which extend towards the surface at each end of the incision.

With either type of sectional plug, however, I preferably bevel the adjacent ends h as shown in Figs. 7 to 9 inclusive, so that there is no transverse break in the grain structure. A further purpose in beveling the adjacent ends of the sectional plug is that when said plug pieces are driven in place they are driven toward the base portion of the incision and also towards each other and such beveled ends tend to form two engaging wedge-like faces which slide upon each other and lock the sectional plug in place. In fact, the wedge-shaped ends tend to compress the engaging portions of the plugs in the incision so that the portions extending out of said incision overlie the latter a substantial distance, as is shown in Fig. 10. The compression of said plug-like patches tends to produce a "lock-joint" which bears tightly along the side of the incision so as to prevent said plug from becoming loose and dropping out.

As diagrammatically in Figs. 9 and 10, the excess portions of said plug-like pieces are dressed off and when so dressed the

plug is not easily detected, because it conforms generally to the divergent conditions of the grain structure at each side of the defect.

5 As has been brought out heretofore, my method permits patches to be used in which the sides of the patch may be made to coincide exactly with the side of the incision without requiring "draft" and yet the 10 patches are made from continuous strips of uniform cross-section. That is, my method permits wedge-shaped patches to be used without requiring that such patches be cut to fit each incision, as has been necessary 15 heretofore.

I claim:

1. In the art of woodworking, the method of patching a board having a surface imperfection, consisting in cutting away such 20 imperfection by forming an incision extending lengthwise of the grain of said board, and wedge-shaped in cross-section, and placing in the incision thus made a plug comprising a plurality of elongated 25 glued pieces corresponding in grain structure and quality to the remainder of such surface, each of said pieces being correspondingly wedge-shaped in cross-section and of substantially greater width than the 30 depth of such incision, one of said pieces being arranged with one end seated further into the incision than the other so that its longitudinal centerline makes a substantial angle with such surface, and then forcing 35 such latter piece endwise toward the other pieces and towards the base of such incision, whereby all of such pieces are secured in said incision with their ends in abutment, dressing off the excess portion of 40 such plug not fitted into the incision.

2. In the art of woodworking, the method of patching a board having a surface imperfection, consisting in cutting away such imperfection by forming an incision extending lengthwise of the grain of said board, and having its oppositely disposed ends narrowing to points, and placing in the incision thus made a plug comprising a plurality of elongated glued 55 pieces of uniform, wedge-shaped cross-section, and corresponding in grain structure and quality to the remainder of such surface and forcing such pieces endwise towards each other and towards the base of such incision, whereby such pieces are secured in said incision with their ends in abutment, dressing off the excess portion of such plug not fitted into the incision.

3. In the art of woodworking, the 60 method of patching a board having a surface imperfection, consisting in cutting away such imperfection by forming an incision extending lengthwise of the grain of said board, and having the ends of its base portion inclined towards the surface of

such board to make a substantially obtuse angle therewith, and placing in the incision thus made a plug comprising a plurality of elongated glued pieces corresponding in grain structure and quality to the remainder of such surface, and in length and in number to the angular portions of the base thus formed, one piece being arranged parallel to each angular base portion and then seating such pieces into such incision by forcing them endwise into the incision and relatively toward each other. 70 75

4. In the art of woodworking, the method of patching a board having a surface imperfection, consisting in cutting away such imperfection by forming an incision extending lengthwise of the grain of said board, and having the ends of its base portion inclined towards the surface of such board to make a substantially obtuse 80 angle therewith, the remainder of such base portion being substantially parallel to such surface, and placing in the incision thus made a plug comprising a plurality of elongated glued pieces corresponding in grain structure and quality to the remainder of such surface and in length and in number to the angular portions of the base thus formed, each piece being arranged substantially parallel to its adjacent base portion, and then forcing the end pieces endwise towards each other and downwardly towards the remaining piece fitted into the parallel portion of the base of such incision, whereby such pieces are 85 secured in said incision with their ends in abutment, dressing off the excess portion of such plug not fitted into the incision, as 90 they are seated into the latter. 95

5. In the art of woodworking, the 100 method of patching a board having a surface imperfection, consisting in cutting away such imperfections by forming an incision extending lengthwise of the grain of said board, and placing in the incision 110 thus made a plug comprising a plurality of elongated glued pieces, each having beveled ends, and corresponding in grain structure and quality to the remainder of such surface, arranging said pieces, respectively, so that their beveled ends abut, and forcing such pieces endwise towards each other and towards the base of such incision, whereby such pieces are secured in said incision with their ends in abutment, 120 dressing off the excess portion of such plug not fitted into the incision. 115

6. In the art of woodworking, the method of patching a board having a surface imperfection, consisting in cutting away such imperfection by forming an incision extending lengthwise of the grain of said board, wedge-shaped in cross section, and having its oppositely disposed ends narrowing to points, then placing in the incision thus 125 130

made a plug comprising a plurality of elongated glued pieces corresponding in grain structure and quality to the remainder of such surface, each of said pieces being correspondingly wedge-shaped and of substantially uniform cross-section and of substantially greater width than the depth of such incision, and forcing such pieces endwise towards each other and towards the base 10 of such incision, whereby such pieces are secured in said incision with their ends in abutment, dressing off the excess portion of such plug not fitted into the incision.

7. In the art of woodworking, the method 15 of patching a board having a surface imperfection, consisting in cutting away such imperfection by forming an incision extending lengthwise of the grain of said board, wedge-shaped in cross-section, having its oppositely disposed ends narrowing to points and having the ends of its base portion inclined towards the surface of such board to make a substantially obtuse angle therewith, the remainder of such base portion being 20 substantially parallel to such surface, then placing in the incision thus made a plug comprising a plurality of elongated glued pieces corresponding in grain structure and quality to the remainder of such surface and 25 in length and in number to the angular portions of the base thus formed, each piece being arranged substantially parallel to its adjacent base portion, and each of said pieces being correspondingly wedge-shaped 30 and of substantially uniform cross-section and of substantially greater width than the depth of such incision, then forcing such end pieces towards each other and downwardly towards the remaining piece fitted into the 35 parallel portion of the base of such incision, whereby such pieces are secured in said incision with their ends in abutment, dressing off the excess portion of such plug not fitted into the incision.

8. In the art of woodworking, the method 40 of patching a board having a surface imperfection, consisting in cutting away such imperfection by forming an incision extending lengthwise of the grain of said board, wedge-shaped in cross-section, having its oppositely disposed ends narrowing to points, and having the ends of its base portion inclined towards the surface of such board to

make a substantially obtuse angle therewith, the remainder of such base portion being 45 substantially parallel to such surface, then placing in the incision thus made a plug comprising a plurality of elongated glued pieces each having beveled ends, and corresponding in grain structure and quality 50 to the remainder of such surface and in length and in number to the angular portions of the base thus formed, each of said pieces being correspondingly wedge-shaped in cross-section and of substantially greater 55 width than the depth of such incision, then arranging said pieces, respectively, so that their beveled ends abut, and forcing such pieces endwise towards each other and towards the base of such incision, whereby 60 such pieces are secured in said incision with their ends in abutment, dressing off the excess portion of such plug not fitted into the incision.

9. The method of patching a board having a surface imperfection, characterized by cutting away such imperfection by forming an elongated incision in such surface, and fitting into such incision a plug comprising a plurality of pieces, one of said pieces being 65 driven endwise, and downwardly into such incision.

10. The method of patching a board having a surface imperfection, characterized by cutting away such imperfection by forming 70 an elongated incision in such surface, and fitting into such incision a plug comprising a plurality of pieces, one of said pieces being driven endwise, and downwardly into such incision, said incision being wedge-shaped in 75 section, and of proportions similar to the section of said incision.

11. The method of patching a board having a surface imperfection, characterized by cutting away such imperfection by forming 80 an elongated incision in such surface, and fitting into such incision a plug comprising a plurality of pieces, one of said pieces being driven endwise, and downwardly into such incision, said incision being wedge-shaped in 85 section, and cigar-shaped in plan, said latter piece being of uniform continuous, wedge-shaped section, and of proportions similar to the section of said incision, and driven inwardly from one of said cigar-shaped ends.

JOHN C. DE PENNING.
